UNITED STATES PATENT OFFICE.

WILLIAM KRAEMER, OF CHICAGO, ILLINOIS.

DESIGN FOR A STAMPING-MACHINE FRAME.

SPECIFICATION forming part of Design No. 33,004, dated July 24, 1900.

Application filed June 22, 1900. Serial No. 21,242. Term of patent 3½ years.

To all whom it may concern:

Be it known that I, WILLIAM KRAEMER, a citizen of the United States, residing at Chicago, in the county of Cook and State of Illinois, have invented and produced a new and original Design for Stamping-Machine Frames, of which the following is a specification, reference being had to the accompanying drawings, forming part thereof.

Figure 1 is a front view in elevation of a frame, showing my new design. Fig. 2 is an edge or side view thereof; and Fig. 3 is a horizontal sectional view, taken on line 3 3 of Fig. 1, looking in the direction indicated by the arrows.

As shown in the drawings, the leading or material feature of my design consists of an upright supporting-piece A, having at its bottom a flat circular base B, to which the supporting-piece is joined by an enlargement b, cylindrical in shape. The supporting-piece A comprises two portions or standards C and C', each of which is formed on its front and rear surfaces with longitudinal channels c and are united a little above their middle by means of a connecting portion D, which is also provided with channels d on its front and rear surfaces. The portion D is formed with a vertical cylindrical opening d', which communicates with the openings E and E' in the

supporting-piece. The upper portions of the standards or parts C and C' are formed on their front and rear surfaces with channels c', irregular in shape. The upper portion of each of the standards C and C' is formed with a transverse cylindrical opening e, and the upper ends of said standards are round, as shown. On the rear surfaces of the standards C and C' are formed transverse curved enlargements e', each of which is provided with a cylindrical opening e'', which openings intersect the lower portion of the opening E'. (Shown in Fig. 1 of the drawings.) The front part of the supporting-piece just below the opening E' is provided with rounded enlargements g, each having an opening g', cylindrical in shape.

Having described my invention, what I claim as new, and desire to secure by Letters Patent, is—

The design for a frame for a stamping-machine, substantially as herein shown and described.

In testimony whereof I have signed my name to this specification in the presence of two subscribing witnesses.

WILLIAM KRAEMER.
